UNITED STATES PATENT OFFICE.

THEODORE H. BROWN, OF VIROQUA, WISCONSIN.

BROOM.

SPECIFICATION forming part of Letters Patent No. 604,000, dated May 10, 1898.

Application filed September 9, 1897. Serial No. 651,144. (No model.)

To all whom it may concern:

Be it known that I, THEODORE H. BROWN, a citizen of Great Britain, (but having declared my intention to become a citizen of the United States,) residing at Viroqua, in the county of Vernon and State of Wisconsin, have invented certain new and useful Improvements in Brooms; and I do hereby declare the following to be a full, clear, and exact description of the invention, such as will enable others skilled in the art to which it appertains to make and use the same.

My present invention relates to an improvement in brooms, the object being to construct a broom in a manner to permit its manufacture in a minimum space of time and to insure flexibility and durability of the completed article. To the accomplishment of this general object and others subordinate thereto my invention consists in providing a sheet-metal receptacle or shield, in which the broom-corn is designed to be inserted, with a series of peripheral notches for the reception of the broom-wires and pointed projections alternating with the notches designed to facilitate the sewing with wire.

Referring to the drawings, Figure 1 is a general view of the completed broom. Fig. 2 is a view of the broom during its manufacture and before the shield has been pressed or the wires attached. Fig. 3 is a detail perspective view of the shield detached.

Referring to the numerals on the drawings, 1 indicates a sheet-metal shield or receptacle substantially cup-shaped and provided in its bottom with a handle-opening 2 and around its upper edge with a series of alternating substantially circular notches or eyes 3 and pointed projections 4. The notches 3 are formed in a manner to provide constricted throats 5, designed to permit the introduction of the binding-wires, to be referred to, but to tend to prevent their displacement.

In the course of the manufacture of the broom the shield or receptacle 1 is placed between suitable clamping-jaws, and an elongated wooden handle 6 is passed through the handle-opening 2 until its upper end is located a sufficient distance below the upper edge of the shield. The broom-corn is now dropped endwise into the receptacle until it has been sufficiently filled, at which time the

clamping-jaws are actuated to compress the cup-shaped shield until it assumes the proper elliptical form to shape the broom as desired. 55 The handle is then secured by passing nails, bolts, or the like 7 through the shield and the inner end of the handle, as indicated. A wire is then passed through the notches and its ends connected, whereby the broom-corn 60 is bound. The pointed projections are now slightly bent inward against the broom-straw and the article is complete. By constructing the broom in this manner comparatively short straws may be used and the necessity for as- 65 sorting the straws before proceeding with the manufacture of the broom is eliminated, as their introduction into the receptacle or shield properly distributes their ends, and it is unnecessary to employ long straws, as ordinary, 70 and thereafter sever the bound ends at the desired point; but while the present embodiment of the invention appears at this time preferable I do not desire to limit myself to the structural details illustrated and de- 75 scribed, but reserve the right to change, modify, or vary such details within the scope of my invention.

What I claim is—

1. In a broom, the combination with the 80 handle and straws, of a receptacle designed to receive the straws and provided with a handle-aperture in its bottom, and with a series of notches in its upper edge, and a binding-wire surrounding the broom and passing 85 through the notches, substantially as specified.

2. In a broom, the combination with the straws and handle, of a receptacle designed to receive the straws and provided with a 90 handle-aperture in its bottom and with a series of alternating notches and inwardly-bent pointed projections around its upper edge, and a binding-wire passed around the broom and through the notches, substantially as de- 95 scribed.

In testimony whereof I have signed this specification in the presence of two subscribing witnesses.

THEODORE H. BROWN.
